UNITED STATES PATENT OFFICE.

WILL H. MORGAN AND HENRY J. MORGAN, OF SAN FRANCISCO, CALIFORNIA.

PIANO-ACTION PROTECTOR.

Application filed March 7, 1922. Serial No. 541,807.

To all whom it may concern:

Be it known that WILL H. MORGAN and HENRY J. MORGAN, citizens of the United States of America, residing at San Francisco, in the county of San Francisco and State of California, have invented new and useful Improvements in Piano-Action Protectors, of which the following is a specification:

10 The object of the invention is to provide a simple and efficient means for protecting the interior of a piano particularly of the grand or horizontal type to prevent access of dust and moisture to the action, strings, 15 sound board, and clothing and particularly to provide a means for this purpose which may be so designed and secured as to permit of leaving it in place whether the piano is in use or not or is open or closed to the 20 end that if desired it may remain permanently in position; and with these objects in view the invention consists in a construction and combination of parts of which a preferred embodiment is shown in the accompanying drawings, wherein:

Figure 1 is a plan view of the body portion of a piano of the grand or horizontal type fitted with a protector constructed and secured in accordance with the invention.

30 Figures 2 and 3 are sectional views respectively on the planes indicated by the lines 2—2 and 3—3 of Figure 1 to show the means for respectively securing the side and keyboard edges of the protector to the piano casing.

Figure 4 is a detail sectional view to show the construction of a preferred form of eyelet.

Figure 5 is a sectional view similar to Figures 2 and 3 to show a modified arrangement of and means for securing the cushion to which the edge of the protector is anchored at the keyboard end of the instrument.

The protector consists essentially of a continuous sheet 10 of felt or its equivalent of a size and contour corresponding accurately with the interior of the frame or casing 11 of the instrument but preferably slightly over-size so that when secured in place and

50 subjected to tension to support the intermediate portion thereof out of contact with the strings of the instrument, the peripheral edge bends or folds upward slightly against the inner surface of the frame or casing so as to insure a perfectly air-tight and dust proof joint. The means for securing the

protector detachably in position in the frame or casing may be variously constructed but a simple and preferred arrangement involves the use of a plurality of hooks 12 of which the shanks may be threaded to engage the material of the casing and of which the upturned tongues 12^a are inclined outwardly and form an acute angle with the shanks 12^b so that eyelets 13 which are secured in the fabric of the protector sheet at a short interval inward from the edge thereof rest in the acute angle with the projecting edge portions of the protector deflected upwardly and lying in contact with the surface of the casing wall as indicated.

This construction and arrangement of fastening means is particularly adapted for the side and rear end edges of the protector whereas at the front or keyboard end thereof it is preferable to provide for a slightly different means of attachment which is also adapted to permit of tensioning the protector longitudinally, and to this end as shown in Figure 3 a cushion 14 is set into the frame 80 of the instrument as for example between the molding strip 15 and the metallic frame 16, the insertion thereof being accomplished by temporary removal of the molding strip, and said cushion which projects slightly beyond the edge of the molding strip being of felt or other fibrous material adapting it to form a seat for pins 17 extended through the protector sheet near its front edge. By disposing these pins in a somewhat oblique position it will be obvious that the edge of the protector may be drawn into close contact with the frame or more properly the edge of the molding strip, when the construction shown in Figure 3 is employed, to prevent the passage of dust and at the same time exclude moisture.

In the modified construction illustrated in Figure 5 the cushion 14^a is forced down between the casing 11 and the frame 16 where it may be held either by compression 100 or by any suitable fastening means such as glue for engagement by the pins 17^a which engage the protector sheet near its edge.

The arrangement of the protector sheet 105 under a tension as above indicated adapts it to perform its function of protecting the interior mechanism of the instrument without interfering with the operation thereof and effectually prevent the accumulation of dust 110 on the felt clothing elements and upon the action, strings, frame, etc., including the

sound board, and also prevent the rusting of the strings which occurs ordinarily under the most favorable conditions to the ultimate detriment of the instrument and depreciation of the tonal qualities thereof.

Referring to Figures 2, 3 and 5, it is to be noted that the protecting felt 10 is disposed in order to protect the strings *b*, the hammers *a* of the piano action (not shown) and also to avoid the collection of dust on these parts as well as on the string plate *c* and the sounding boards *g*. In other words, the string plate *c* with the strings *b* and the hammers *a*, together with the sounding boards *g*, are below the felt, although these parts may be otherwise arranged. The strings *b* and the string plate *c* with the hammers *a* and sounding boards *g* are similar to those in Patent No. 1,032,608, dated July 16, 1912. The sounding boards *g* are shown in dotted lines. It is to be understood that the protecting felt 10 may be applied to constructions of pianos, other than the type disclosed in the above mentioned patent.

Having described the invention, what is claimed as new and useful is:—

1. A protector for the interior mechanism of pianos consisting of a flexible textile sheet secured within the casing of the instrument above the plane of the strings thereof and in close edge contact with the inner surface of the casing.

2. A protector for the interior mechanism of pianos consisting of a flexible textile sheet secured within the casing of the instrument above the plane of the strings thereof and in close edge contact with the inner surface of the casing, the means for securing the edges of the protector being adapted for maintaining the sheet under transverse and longitudinal tension.

3. A protector for the interior mechanism of pianos consisting of a flexible textile sheet secured within the casing of the instrument above the plane of the strings thereof and in close edge contact with the inner surface of the casing, the means for securing the edges of the protector being adapted for maintaining the sheet under transverse and longitudinal tension with the edges of the protector deflected upwardly at the line of contact with the surface of the casing.

4. A protector for the interior mechanism of pianos consisting of a flexible textile

sheet secured within the casing of the instrument above the plane of the strings thereof and in close edge contact with the inner surface of the casing, the means for securing the edges of the protector being adapted for maintaining the sheet under transverse and longitudinal tension and consisting of hooks carried by the casing walls and eyelets carried by the protector sheet.

5. A protector for the interior mechanism of pianos consisting of a flexible textile sheet secured within the casing of the instrument above the plane of the strings thereof and in close edge contact with the inner surface of the casing, the means for securing the edges of the protector being adapted for maintaining the sheet under transverse and longitudinal tension and consisting of hooks carried by the casing walls and eyelets carried by the protector sheet, said eyelets being set back from the edge of the sheet to permit of deflection of the edges of the latter at the line of contact with the surface of the casing.

6. A protector for the interior mechanism of pianos consisting of a flexible textile sheet secured within the casing of the instrument above the plane of the strings thereof and in close edge contact with the inner surface of the casing, the means for securing the edges of the protector being adapted for maintaining the sheet under transverse and longitudinal tension and consisting of hooks carried by the casing walls and eyelets carried by the protector sheet, the tongues of the hooks being disposed at an outward inclination to form an acute angle with the shanks thereof to constitute a seat for the eyelets.

7. A protector for the interior mechanism of pianos consisting of a flexible textile sheet secured within the casing of the instrument above the plane of the strings thereof and in close edge contact with the inner surface of the casing, the means for anchoring the front or keyboard edge of the sheet consisting of cushions secured in the instrument frame and pins extending through the edge portion of the sheet and engaging the cushion.

In testimony whereof they affix their signatures.

HENRY J. MORGAN.
WILL H. MORGAN.
